UNITED STATES PATENT OFFICE.

JAMES H. OWEN, OF NEWBURGH, NEW YORK.

FIRE-ALARM.

1,135,916.

Specification of Letters Patent. Patented Apr. 13, 1915.

Application filed March 20, 1914. Serial No. 826,086.

To all whom it may concern:

Be it known that I, JAMES H. OWEN, a citizen of the United States, residing at Newburgh, in the county of Orange and State of New York, have invented new and useful Improvements in Fire-Alarms, of which the following is a specification.

The general object of this invention is to effect the closing of an electric circuit which includes an audible signal, such as a bell, in the event of the occurring of fire in a room wherein the invention is placed.

And to these ends the invention consists of a base provided with metallic arms adapted to be wired to an electric audible alarm, a circuit closing member adapted to contact with the arms and means for holding the plate out of contact and in spaced relation to the arms, the said means being formed of a substance having a relatively low melting point.

Other objects will appear and be better understood from that embodiment of my invention, of which the following is a specification, reference being had to the accompanying drawings forming part hereof, in which:

Figure 1 is a diagrammatic view of my invention. Fig. 2 is a cross sectional view of the same.

As shown in the drawings the invention is composed of the base 5, the metallic arms 6—6, the circuit closing plate 7, and the fusible supporting means 8.

The base 5 is preferably formed of a non-conductive material such as fiber, rubber or the like, and may be any shape if desired. The base is adapted to be positioned on the ceiling of a room and for the purpose of receiving the securing screws 9, the base is pierced at suitable points. Centrally carried by the base is a stud 10, which is provided with a suitable head 11, and is sufficiently long so as to extend down beyond the arms 6, as shown in Fig. 2. This stud is provided for the purpose of slidingly carrying the metallic plate 7. The arms 6—6 may be made of any conductible metal such as copper, brass, or the like, and are substantially yoke-shape and insulated from each other by means of the non-conducting base 5. The arms may be secured to the base in any suitable manner, and are arranged in spaced relation at either side of

the stud 10, as shown. One portion of the arms is screw threaded as indicated at 12—12, so as to have adjustably mounted thereon the nuts 13—13, which are adapted to bind against suitable shoulders 14—14, and thus secure to the arms the ends of wires 15—15. These wires form the circuit a, in which is located an electric bell 16, operated by the cells 17, when the circuit is closed by the plate 7 contacting with the arms 6—6.

The plate 7 may be formed of any suitable metal such as copper, brass or the like, and for the purpose of illustration, the same is shown in the form of a disk. This plate is centrally pierced so as to be loosely mounted on the stud 10, and is arranged to drop by force of gravity and span the arms 6 to form a contact therebetween when the device is in use. In order to hold the plate out of contact with the arms, a means 8 is provided on the stud 10, which is preferably formed of wax, or some similar substance of a relatively low melting point.

It will be readily seen that in the event of a fire occurring in the room in which the device is located, the heat-waves will ascend and thus melt the wax 8, whereupon the plate will gravitationally drop and contact with the arms 6—6, thus closing the circuit and operating the alarm signal.

It is obvious that those skilled in the art may vary the details of construction and arrangements of parts without departing from the spirit of my invention and therefore I do not wish to be limited to such features except as may be required by the claim.

What is claimed as new is:

A circuit closer comprising a support, metallic arms mounted on the support and insulated one from the other, a stud attached to the support and disposed between the arms and transversely thereof, a plate slidably mounted on the stud between the arms and the support and being greater in diameter than the space between the arms, and fusible material applied to the stud and holding the plate spaced from the arms.

In testimony whereof I affix my signature in presence of two witnesses.

JAMES H. OWEN.
